UNITED STATES PATENT OFFICE.

DARIUS T. WADHAMS, OF OSWEGO, NEW YORK, ASSIGNOR TO NIEL GRAY, JR., OF OSWEGO, NEW YORK.

PAPER-CUTTING MACHINE.

1,191,750.

Specification of Letters Patent.

Patented July 18, 1916.

Application filed July 28, 1913. Serial No. 781,606.

To all whom it may concern:

Be it known that I, DARIUS T. WADHAMS, a citizen of the United States, residing at Oswego, in the county of Oswego and State 5 of New York, have invented new and useful Improvements in Paper-Cutting Machines, of which the following is a specification.

This invention embodies improvements in paper cutting machines which are particularly designed to contribute to accuracy and effectiveness in the cutting operation. The improved features thereof comprise a locking device for the back-gage customarily employed, this locking device operating rigidly to clamp the back-gage in its adjusted position and operating connections therefor whereby the locking device may conveniently be actuated by the operator.

It also includes novel features of construction and mode of operation as hereinafter described.

In the accompanying drawings wherein one of the possible embodiments of my invention is shown, the reference numerals of 25 this description are applied to the corresponding parts in the several views.

The views show in Figure 1 a side elevation of a machine embodying the various features of my invention with a portion 30 broken away better to illustrate certain parts. Figs. 2 and 3 show in side elevation and in cross-section, respectively, my improved clamping device for the gage and Fig. 4 illustrates in front elevation the detail of the operating connections for the clamping device.

In the figures 1 indicates the usual supporting standard for the table 2. The standard is provided with uprights 3 having finished front surfaces 5 to coact with guide-bars 6 in forming guide-way bearings for the usual knife-stock 8 carrying the knife-blade 10. The guide-bars 6 are bolted to the front of the standards by securing bolts 7. 45 The parts so far referred to are of usual construction and are shown in Fig. 1 at one side of the machine only but it will be understood that the guide-way for the knife-stock is duplicated at the opposite side of the machine and that the knife is operated therein in the customary manner to descend upon the work to be cut.

A suitable back-gage 12 is provided for the purpose of correctly positioning the work upon the table. The back-gage 12, as

here shown is supported on the table rear portion and is arranged to slide thereon toward and from the knife and for the convenient adjustment of the gage it is provided with a depending attachment lug or gib-piece 14 to which is attached an operating cable 15. As shown in Fig. 1 the cable ends are attached to hooks 16 adjustably threaded in the attachment piece and the cable is forwardly extended around a forward drum 17 60 fulcrumed on the under side of the table forward portion, the drum having a hand wheel 18 attached thereto. The cable is carried rearwardly over pulley 20 journaled on the rear extremity of the table. 70

As will be best understood by reference to Fig. 3 the table rear extension upon which the back-gage moves, is provided with a central slot 22 and fitted thereto is the guide-piece 24 bolted to the under side of the gage 12 by securing bolts 25, which pass through the gage and are threaded into the attachment piece 14, and by an additional bolt 26 threaded into the guide-piece 24. The bolts 25 are thus arranged to secure both the guide 80 and the attachment piece 14 to the under side of the gage, the latter being arranged beneath the table and formed to act in a further capacity now to be described.

An important feature of the present invention resides in a locking device adapted positively to lock the back-gage 12 against movement after it has been correctly positioned on the table. For this purpose I have devised a mechanism acting directly to 85 clamp the gage onto the table and I have formed the attachment piece in the following manner so as to form a support for the clamping parts. Referring to Figs 2 and 3 the attachment lug 14 will be seen to have 95 formed in its upper portion a central cross-slot 28 and fitted in the cross-slot to bear on the under portion of the table is the clamp strap 30. This clamp strap 30 is arranged to be forced into clamping engagement with the table under the action of a cam 32 keyed onto an actuating shaft 33 by an elongated key. The shaft 33 extends from front to rear parallel to the table slot 22 and it is supported in the respective front 100 and rear journal bearings 36-37. The attachment piece 14 is provided with the depending ears 38-38 apertured to fit the shaft 33 and between these ears the cam 32 is confined to move with the gage; the key 110

40 of the cam is fitted to an elongated key-slot 42 in shaft 33 of sufficient length to permit of the desired reciprocal movement of the gage.

5 On the front of the standard is arranged a bearing bracket 45 for an operating shaft 46 having on its front end the hand lever 48 and on its rear end the segment gear 49 in engagement with coacting segment gear 50 fixed on the locking or actuating shaft 33. By manipulating the lever 48 which is conveniently arranged for the operator, the actuating shaft 33 is rotated, communicating a like movement to the cam connected thereto. The cam then acts to force the clamp strap into binding engagement with the table under side; this effect being obtained by the engagement of the cam with the lower face of a bar or clip 52 attached 15 rigidly, but adjustably, to the clamp strap by means of the connecting bolts 53—53 having locking nuts 54 thereon. The locking nuts provide, by their adjustment, for accurately adjusting the relation of the clip 20 and cam and to compensate for wear on the parts.

The operation of the cam 32 as stated is to force the clamp-strap 30 into binding engagement with the under portion of the 30 table and in so doing there will be a resulting downward force exerted on the locking shaft 33 on the further movement of the cam after the strap has engaged the table. By reason of the close running fit of the 35 locking shaft to the ears 38 of the attachment piece 14 and the give or resiliency inherent in the locking shaft the downward force exerted by the cam will be transmitted to the attachment piece whereby the gage 40 will be pulled downwardly into clamping engagement with the upper surface of the table.

The securing means for the clamp as customarily employed is here indicated in Fig. 45 1 and consists of the clamping jaws 56—56' arranged between them to clamp tight the rim of the hand wheel 18 when a hand lever 58 is operated. The securing means thus provided suffices in satisfactorily securing 50 the gage when cutting light work and when the cable is perfectly taut. In the event of the cutting of heavy piles however, the stretch of the cable when the pile is jogged against the gage is sufficient to cause a shifting 55 of the gage from correct position. By the employment of my improved gage clamping device just described the gage may rigidly be clamped directly to the table to withstand any shock to which the gage is 60 subjected thereby to insure of accurate positioning of the pile.

Having described my invention I claim:

1. A machine of the character described having a supporting frame and a table thereon for the work to be cut, a gage for

the work arranged to be movable on the table and locking means therefor connected to the gage and operative to effect a clamping engagement with the table whereby the gage is rigidly clamped in position.

2. A machine of the character described having a supporting frame and a table thereon for the work to be cut, a gage for the work arranged to be movable on the table, locking parts for the gage connected thereto and supported below the table and actuating means for the locking parts operative to effect a clamping engagement between the locking parts and the table.

3. A machine of the character described having a supporting frame and a table thereon for the work to be cut, a gage for the work arranged to be movable on the table rear portion, means to move the gage on the table, locking means for the gage connected thereto and actuating means therefor operative to cause the locking means to effect clamping engagement with the table, said actuating means being extended forwardly to the front of the machine.

4. A machine of the character described having a supporting frame and a table thereon for the work to be cut, a gage for the work arranged to be movable on the table, said table having a guide-slot therein, a guide element on the gage fitted to the slot, an attachment piece secured to the gage and depending therefrom beneath the table, an engaging part arranged to engage the under surface of the table, an actuating cam adapted to work between the attachment piece and engaging part to exert an upward force on the engaging part and a downward force on the attachment piece to effect clamping engagement with the upper and lower surfaces of the table rigidly to secure the gage and means to operate the actuating cam.

5. A machine of the character described having a supporting frame and a table thereon for the work to be cut, a gage for the work arranged to be movable on the table, said table having a guide-slot therein, a guide-element on the gage fitted to the slot, an attachment piece secured to the gage and depending therefrom beneath the table, opposed ears on the attachment piece, an actuating shaft fitted to said ears, a locking cam slidably keyed on the actuating shaft and confined between the ears, and means to rotate the actuating shaft to cause the locking cam to effect the clamping of the gage in position.

6. A machine of the character described having a supporting frame and a table thereon for the work to be cut, a gage for the work arranged to be movable on the table, said table having a guide-slot therein, a guide element on the gage fitted to the

slot, an attachment piece secured to the gage and depending therefrom beneath the table, opposed ears on the attachment piece, an actuating shaft suitably journaled and fitted to said ears, a locking cam slidably keyed on the actuating shaft, a two piece engaging part interposed between the cam and the table under portion, adjustable connections between the two pieces forming 10 said part, an operating shaft journaled at the front of the machine, connections be-

tween the operating and the actuating shafts, an operating lever on the operating shaft and means to move the gage on the table. 15

In testimony whereof I have signed my name to this specification in the presence of two subscribing witnesses.

DARIUS T. WADHAMS.
